(57) **CLAIM**

We claim the ornamental design for a fluid-mixing device for a catalytic converter, as shown and described.

DESCRIPTION

FIG. 1 is a front perspective view of a fluid-mixing device for a catalytic converter showing our new design;

FIG. 2 is a rear perspective view thereof;

FIG. 3 is a front view thereof;

FIG. 4 is a rear view thereof;

FIG. 5 is a top plan view thereof;

FIG. 6 is a bottom plan view thereof;

FIG. 7 is a right side view thereof;

FIG. 8 is a left side view thereof; and,

FIG. 9 is a perspective view showing the article in use.

The features shown in broken lines in the drawings depict environmental subject matter only and form no part of the claimed design.
